United States Patent

Des. 241,558
Patented Sept. 21, 1976

241,558

ANIMAL IDENTIFICATION TAG

Jackson T. Schwindt and Maurice A. Whitney, Cody, Wyo., assignors to Y-Tex Corporation, Cody, Wyo.

Filed Apr. 25, 1975, Ser. No. 571,751

Term of patent 14 years

Int. Cl. D30—08

U.S. Cl. D30—43

FIG. 1

FIG. 5

FIG. 6

FIG. 2

FIG. 3

FIG. 4

FIG. 1 is a perspective view of an animal identification tag, showing our new design;

FIG. 2 is a front elevational view;

FIG. 3 is a right side elevational view;

FIG. 4 is a rear elevational view;

FIG. 5 is a top plan view; and

FIG. 6 is a fragmentary cross-sectional view taken along line 6—6 of FIG. 2.

We claim:

The design for an animal identification tag, substantially as shown and described.
